UNITED STATES PATENT OFFICE.

WILLIAM H. BAKER, OF MONTREAL, QUEBEC, CANADA.

CLOTH-ROLL MOUNTING FOR LOOMS.

Application filed January 15, 1923. Serial No. 612,809.

This invention relates to improvements in the mounting of cloth rolls in looms and is a continuation of my former application Serial No. 523140. The objects of the invention are to provide for the accommodation of a larger cloth roll than is customary and to provide for the quick and easy removal of such larger and therefore heavier roll.

10 A further object is to provide means for swinging a cloth roll clear of the loom preparatory to removal with a view to facilitating the removal and protecting the loom from damage in the event of the heavy cloth roll falling in course of removal from the loom to trucks or other transporting devices.

20 Various other objects and advantages may be ascertained from the following description.

While the subject matter of the present invention is particularly advantageous when used in connection with vertical or other looms in which the cloth roll is at 25 the top of the loom, it must be understood that the invention is in no way thus limited but is applicable to other types of looms.

30 Looms in use at the present time have for the most part very limited capacity or accommodation for the cloth roll, with the result that it is usually necessary to cut the cloth and remove the roll several times during the emptying of a single warp beam. This limitation in the size of the cloth 35 roll, which is due to the positioning of the roll in ordinary looms, limits the length of cloth that can be woven and results in the production of comparatively short pieces which for further treatment are fastened 40 together so that the output of a number of looms may be handled as a continuous length in rope form or otherwise. The advantages to be derived from reducing the number of joins and the wastage resulting therefrom 45 will be apparent to those skilled in the textile industry. Another factor which serves to limit the permissible size of cloth rolls is the great weight thereof, but with modern appliances this is no insurmountable difficulty if the roll is conveniently disposed. In 50 looms where the cloth roll is placed near the ground the question of weight may be disregarded but in vertical looms or in others where the cloth roll is mounted above any of the working parts of the loom the 55 matter of lifting the heavy cloth roll clear

of the loom is hazardous in that if the roll is dropped the loom is almost certainly broken.

According to the present invention the foregoing disadvantages are overcome and provision is made for the growth of cloth rolls to large size and for the easy handling thereof during removal from the loom without danger of a falling roll damaging the 60 loom. These results are in part achieved by so positioning the sand roll that there is ample space for a larger cloth roll. Preferably the cloth roll is placed above the loom with the result that the loom itself 65 does not impose any limitation on the size to which the cloth roll may grow excepting the ability of the mechanism to support the weight of the roll. Positioning guides are provided for the cloth roll, which guides 70 are movable to quickly and safely lower a cloth roll and at the same time move the roll laterally clear of the loom so that if the roll should fall in transfer from the 75 guides to a truck or other transporting device it will fall clear of the loom. By reason of these provisions an entire warp of the maximum capacity of a loom may be woven into a single piece of cloth of great 80 length. In a vertical loom or in a horizontal 85 loom where the cloth roll is placed above the loom the handling of large and heavy rolls would be difficult if it was necessary to lift the roll down and over the loom and accidents would be frequent, but by reason 90 of the instrumentalities provided according to this invention the lowering and lateral movement of the roll and the transfer to a truck or the like are accomplished mechanically and without hazard to the loom or to 95 workmen.

In the accompanying drawings which illustrate one embodiment of the invention in its application to a vertical loom:—

Fig. 1 is an end elevation of the device 100 with the supporting frame removed and showing the manner of unloading a cloth roll.

Fig. 2 is a front elevation of the device.

Fig. 3 is a plan view of the device.

Fig. 4 is a fragmentary sectional view on the line 4—4, Figure 1.

Fig. 5 is a fragmentary view corresponding to Figure 1 and showing a slight modification.

Referring more particularly to the drawings, 11 designates fragments of a frame-

105

110

work of any suitable sort which may be a part of loom end frames or may be brackets attached to the end frames or any other suitable parts of a loom. In the framework or 5 supports 11 there is revolubly mounted, either directly or by means of spindles 12, a sand roll 13 of any usual or suitable construction and adapted to be operated in any usual or suitable way for the well known 10 purpose of such device. Adjacent the roll 13 and preferably axially parallel therewith a shaft 14 is journalled either in the supports 11 or in any other suitable supports but of necessity in such a manner that the shaft 15 and roll be maintained in their predetermined positions and relations.

A pair of guides 15 are provided to receive the ends of a cloth roll core 16, the guides being formed in any suitable manner, as for 20 instance, by the provision of grooves 17 in which the ends of the core 16 fit loosely so that the core may rotate and also move bodily in the guides. Each guide is preferably closed at its free end as at 18 and provided 25 with a laterally directed opening 19 giving access to the grooves. The guides may be suitably webbed as at 20 for strength. These guides are pivotally mounted each at one end, the mounting preferably being such 30 that the guides may swing or be oscillated about the axis of the sand roll, but this relation to the sand roll is not essential. This pivotal mounting of the guides may be effected in a great variety of ways of which 35 only one is herein illustrated. The illustrated method of mounting the guides comprises the provision for each guide of a member 21 encircling the end of the sand roll, rotatable upon the roll and seated preferably on a reduced portion 22 thereof. This 40 member may conveniently be an ordinary tooth gear or gear segment or may have attached to it in any suitable way a circularly curved series of gear teeth designated 23. One end of a guide is rigidly connected to the member 21 by bolts or rivets as illustrated or otherwise if desired. It is obvious 45 that exactly the same result will be produced if the guide member is formed integral with the encircling or pivoted member 21 and the teeth formed directly thereon or on the member attached thereto. Obviously, the same effect will be produced if the guides 50 are mounted on the frame, concentrically of the sand roll axis.

The shaft 14 is operatively connected with the toothed members 21 or their equivalent, preferably by means of pinions 24 mounted on the shaft and meshing with the teeth 23. It will be understood that any suitable number 60 of gears may be interposed between the pinions and members 21 if desirable or necessary to facilitate operation of the device. Any suitable means, such as a hand-wheel 65 25, may be connected to the shaft 14 to rotate

the same. If desired any usual or suitable mechanism (not shown) may be provided to releasably lock the guides against movement. The angle of movement of the guides is approximately 90° and it is advisable to limit 70 the movement substantially to this angle. One convenient method of thus limiting the angle of movement is to provide stops 26 and 27 on the toothed member or guide in position to engage the shaft 14 or pinions 24, 75 as illustrated. The stops 26 which limit the upward movement of the guides may be so disposed that the guides will swing slightly past the vertical, so that the weight of the cloth roll will serve to hold the stops in engagement with their abutments, as in Figure 1. By such an arrangement the weight of 80 the roll holds the guides against accidental downward swinging. If it is thought undesirable to place entire reliance upon the weight of the roll as a holding means, a releasable locking device, previously alluded to, may be used additionally.

The operation of the device is as follows:—The guides normally extend approximately vertically upward from the sand roll or lean slightly inward from the vertical to the extent permitted by the stops 26 and the cloth roll core is supported on its ends in the 90 guide grooves and rests by gravity on the sand roll. The cloth passes over the sand roll and around the core so that as the sand roll is rotated it rotates the cloth roll. As the cloth roll increases in diameter its core rises in the guides. Cloth may be allowed 95 to accumulate in the roll until the core approaches the upper ends of the guides or to any less size for which there is space available in the loom. Ordinarily the length of 100 the guides beyond the sand roll is greater than the intended radius of the cloth roll so that when the maximum size of cloth roll is formed the roll core will be still some distance below the upper ends of the guides. After the cloth in the roll is severed from 105 the cloth in the loom the shaft 14 is rotated in an appropriate direction and by reason of the gear connection to the guides causes these 110 guides to swing outwardly to a substantially horizontal position, the limit of movement being determined by the stops 27, as illustrated in broken lines, Figure 1. By this 115 movement the cloth roll is lowered from a position above and at rest upon the sand roll to a position of support on the guides at one side of the sand roll. The cloth roll 120 may now be moved out until its core is at the extremities of the guides. The end closures 18 of the guide grooves hold the core of the roll against accidental withdrawal beyond the ends of the guides, the lateral 125 openings 19 being at the lower sides of the guides. This drawing out movement of the roll is for the purpose of disposing the same 130 entirely clear of the loom and the length

of the guides is therefore designed with due regard to the width of the loom and the intended diameter of the cloth roll to attain this result. When the cloth roll is drawn 5 out to the extremities of the guides the ends of its core will drop through the lateral openings 19 and into suitable receptacles, designated 28 and shown in Figure 1, which may be mounted upon a truck or other trans- 10 porting device. By this means it becomes unnecessary for workmen to lift or otherwise support the weight of the cloth roll so that the danger of the same being dropped is entirely eliminated. If desired the position 15 of the stops 27 may be such that the guides come to rest at a very slight upward inclination from the horizontal, so that when lowered the roll will not run out to the ends of the guides of its own weight but will re- 20 quire to be drawn or rolled out. In this way accidents due to improperly placed receptacles 28 or to the absence of same will be avoided. If desired, the openings 19 may be placed on the opposite sides of the guides 25 as shown in Figure 5 so that when the guides are lowered the roll must be lifted out. A fresh core is now inserted in the guides and the same returned to vertical position by rotation of the shaft 24 in a direction opposite to the previous rotation.

Having thus described my invention, what I claim is:—

1. In a loom, a frame, a sand roll rotatably mounted on said frame, a cloth roll core and 35 guides for the ends of said core pivotally supported to swing about the axis of the sand roll with the periphery of the cloth roll continuously in contact with that of the sand roll.
2. In a loom, a frame, a sand roll rotatably mounted on said frame, pivotally oscillatable guides having elongated openings to rotatably and slidably receive the ends of a cloth roll core, and means to so position the guides 45 and cloth roll core that by the action of gravity a cloth roll maintains operative relation with the sand roll and also maintains the guides in position, the said positioning means being operable to move the cloth roll 50 downwardly and laterally of the sand roll to an unloading position.
3. In a loom, a frame, a sand roll journaled thereof, cloth roll guides pivotally related to the frame and designed to move 55 a cloth roll from winding to an unloading position, and means to limit the movement of said guides, whereby the weight of a cloth roll holds the guides throughout the winding in position to maintain the cloth roll in winding relation with the sand roll.
4. In a device of the class described, a pair 60 of pivoted cloth roll guides, toothed rack members connected thereto, pinions meshing with said rack members and means for rotating the pinions to swing the guides about

their pivotal points and supports carried by the toothed members to limit the swing of the guides.

5. In a loom, cloth roll guides having normally upright elongated channels to receive 70 the ends of a cloth roll core, the said channels being closed at their ends so as to limit the travel of said core ends lengthwise of the channels, and having laterally directed openings adjacent said closed ends, and 75 means to swing the guides to substantially horizontal position to lower a cloth roll and enable the roll core ends to be withdrawn by vertical movement through the channel openings.

6. In a loom, cloth roll guides having normally upright elongated channels to receive 80 the ends of a cloth roll core, the said channels being closed at their ends so as to limit the travel of said core ends lengthwise of the channels, and having laterally directed openings adjacent said closed ends, and 85 means to swing the guides to substantially horizontal position and in a direction to dispose the channel openings on the lower sides 90 of the channels, whereby a cloth roll core may escape by gravity from the channels.

7. In a loom, in combination with a sand roll, a pair of guides channelled to receive 95 the ends of a cloth roll core and adapted to position a cloth roll for operative engagement with the sand roll, the said guides being pivotally mounted to swing the cloth roll out of operative engagement with the sand roll, stops connected with the guides, and 100 abutments against which the stops are urged by the weight of a cloth roll to maintain the guides in position to hold the cloth roll in operative relation with the sand roll.

8. In a device of the class described, a 105 guide comprising a pair of substantially parallel spaced rails, one longer than the other, a lateral extension on the longer rail beyond the end of the shorter rail constituting a stop which limits the movement of a 110 cloth roll core lengthwise of the guide and defining with the shorter rail a lateral opening communicating with the space between the rails, means connecting said rails, said guide being swingingly mounted at one end, 115 and means to swing the guide.

9. In a loom in combination with a sand roll, a pair of guides channelled to receive 120 the ends of a cloth roll core, the said guides being pivotally mounted to swing about the axis of the sand roll, a toothed quadrant carried by each guide, a shaft, pinions on said shaft meshing with the guide quadrants, and stops at the ends of the quadrants engageable with the pinions to limit the swing 125 of the quadrants.

10. In a loom, in combination with a sand roll, a pair of guides channelled to receive 130 the ends of a cloth roll core and adapted to position the core for engagement with the

sand roll, the said guides being pivotally mounted, rack and pinion mechanism for swinging the guides from substantially upright to substantially horizontal position, and stops to check the downward movement of the guides slightly above the horizontal, whereby the cloth roll will be prevented from running out on the guides, and further

stops to check the upward movement of the guides slightly past the vertical plane containing the axis, whereby the weight of the cloth roll will hold the guides against return to their lowered position. ¹⁰

In witness whereof, I have hereunto set my hand.

WILLIAM H. BAKER.
